UNITED STATES PATENT OFFICE.

LEWIS R. HEIM, OF DANBURY, CONNECTICUT, ASSIGNOR TO THE HEIM GRINDER COMPANY, OF DANBURY, CONNECTICUT, A CORPORATION OF CONNECTICUT.

GRINDING APPARATUS.

Application filed January 8, 1923. Serial No. 611,393.

This invention relates to grinding, and more particularly to apparatus for grinding cylindrical articles or bodies having a headed or enlarged portion at one end thereof.

One of the objects of this invention is to provide simple apparatus of practical construction and efficient action for grinding articles or bodies of irregular shape, a portion of each of which is substantially cylindrical and another portion of each being of greater radial extent than the cylindrical portion. Another object is to provide apparatus of the above character that will be of simple and convenient yet dependable manual manipulation and conducive to high speed of operation. Another object is to provide a simple and practical apparatus for insuring a reliable and dependable action of the grinding apparatus throughout the portions of the article desired to be ground and for safe-guarding both the grinding apparatus and the article operated upon from injury that might otherwise result because of the irregular shape of the article operated upon. This invention aims also to provide a simple and practical device for rapidly and effectively discharging the work acted upon from the apparatus after operation thereon. Other objects will be in part obvious or in part pointed out hereinafter.

35 The invention accordingly consists in the features of construction, combinations of elements and arrangements of parts as will be exemplified in the structure to be herein-after set forth, and the scope of the application of which will be indicated in the following claims.

40 In the accompanying drawings in which is shown one of various possible embodiments of the mechanical features of this invention.

45 Figure 1 is a side elevation, partly in section and with certain parts omitted to show the construction more clearly;

Figure 2 is a front elevation as viewed substantially on the line 2—2 of Fig. 1; and

Figure 3 is an enlarged detached view in section of certain features shown in Fig. 2. 50

Similar reference characters refer to similar parts throughout the several views of the drawings.

Referring now to the drawings and more particularly to Fig. 2, there is shown a 55 grinding wheel 10, rotatable in any suitable manner at a suitable grinding speed and in the direction of the arrow indicated in this figure, and a regulating wheel 11, rotatable at a relatively low speed for purposes more 60 clearly hereinafter described. The wheels 10 and 11 may be composed preferably of any suitable abrasive material and are suitably mounted for rotation in the direction indicated by the arrow so as to present operative surfaces 10^a and 11^a, respectively, 65 which not only travel in opposite directions with respect to the work operated upon, but also approach each other to present opposed operative portions which coact with or act 70 upon the work operated upon. The wheels 10 and 11, moreover, are preferably so arranged or mounted that they may be adjusted toward or away from one another to accommodate the opposed operative portions 75 thereof to different diameters of work operated upon. They may, for example, be mounted as shown for example in my co-pending application Serial No. 579,566, filed August 4, 1922. 80

The wheels 10 and 11 are preferably encased in a suitable housing, indicated generally at 12, and this housing, which may be secured to the main frame 13 of the machine as by bolts 13^a, is provided at its lower portion substantially intermediate of the two wheels with a horizontally extending bridging section or surface 12^a extending between the rear wall 12^b and the front wall 12^c of the housing 12. This horizontal bridging portion 12^a may be reinforced as by the rib 12^d to insure rigidity and durability of construction. 85 90 100

Upon the horizontally extending bridging or supporting surface 12^a rests a casing 14 in general of a cylindrical shape but

plane-faced on its under side to rest upon the surface 12^a and provided at its forward end (or left-hand end as viewed in Fig. 1) with a downwardly extending lug or plate 15 preferably integrally formed therewith. The plate 15 is provided with a horizontally extending slot 16 through which extends the cap screw 17 for securing the casing 14 in position upon the supporting or bridging member 12^a. The slot 16, moreover, permits the casing 14 and its associated parts to be adjusted horizontally toward or away from either of the wheels.

The casing 14 is adapted to support a work carrier 18 extending between the operative surfaces of the two wheels and, moreover, is adapted also to support and house the mechanism for moving the work support or carrier 18 inwardly or outwardly (as viewed in Fig. 2) between the approaching operative surfaces 10^a and 11^a of the grinding wheel 10 and regulating wheel 11, respectively. As to the detailed features of the latter construction, reference may be had to my above-mentioned co-pending application, but it may at this point be briefly explained that the casing 14 is bored out throughout substantially its entire extent as at 19 to provide a substantially cylindrical bearing or guiding surface, and within the casing 14 is housed for slideable movement therein a substantially cylindrical operating bar 20, at the forward end and under side of which there is integrally formed therewith a rack 21 adapted to mesh with a spur gear 22 supported upon the shaft 23 rotatably mounted between a pair of lugs 24 integrally formed at the forward end of the casing 14. At the right-hand end (as viewed in Fig. 2) of the shaft 23 is mounted an operating handle or lever 25 by means of which and through the gear and rack connection the operating bar 20 is moved within the housing 14.

At two spaced points in the upper surface of the bar 20, preferably one on each side of the wheels 10 and 11 (see Fig. 1), are provided inclined surfaces 26 and 27 with which cylindrical posts 28 and 29 vertically slideable in the vertically extending sleeve portions 30 and 31 respectively of the casing 14 are adapted to cooperate. Thus, referring to Fig. 1, the continuous clockwise rotation of the operating lever 25 will move the operating bar 20 to the right and thus simultaneously move upwardly with a continuous movement the posts 28 and 29 and, vice versa, a reverse movement of the operating lever 25 carries, through the gear 22 and rack 21, the bar 20 to the left to permit the vertical posts 28 and 29 to return to their initial position.

The upper portions of the vertical posts 28 and 29 are provided with vertically extending lugs 28^a and 29^a, centrally slotted

as at 28^b and 29^b, respectively. To the lugs 28^a and 29^a is secured the work carrier 18. Cap screws 28^c and 29^c threaded into the work carrier 18 and passing through the vertically extending slots 28^b and 29^b, respectively, permit the work carrier 18 to be not only rigidly secured to the vertical posts 28 and 29, but also to be adjusted vertically with respect thereto. Moreover, this connection of the work carrier 18 with the vertically moving posts 28 and 29 makes possible also any desired adjustment of the work carrier 18 with respect to the horizontal plane as viewed in Fig. 1; that is, the work carrier 18 may be given whatever inclination with respect to the horizontal that conditions might require.

At this point it might be noted that suitable springs 30^a and 31^a suitably connected with the work carrier 18 and the casing 14 insure the positive downward movement (as viewed in Fig. 1) of the work carrier 18 with the vertically movable supporting posts 28 and 29 in response to a counter-clockwise rotation of the operating lever 25.

The work carrier 18 may conveniently take the form of a bar, generally of rectangular cross section, and aside from extending between the two wheels 10 and 11 extends also beyond the supporting posts 28 and 29 in order to dependably coact with stops 32 and 33 spaced well apart and threaded into suitable bosses in the upper portion of the casing 14. The stops 32 and 33 are positioned in the path of movement of the carrier 18 and act to limit the downward movement of the carrier 18 as viewed in Fig. 1. The stops 32 and 33 are provided at their upper ends with disc-like heads 32^a and 33^a carrying on their outer periphery suitable gradations or indicia, and these gradations extending throughout the entire periphery are preferably decimal fractions of the pitch of the threaded portions of the stops 32 and 33. Coacting with each disc member 32^a and 33^a are the fixed vertically extending posts 34 and 35, respectively, suitably secured to the casing 14. The posts 34 and 35 are graduated as is diagrammatically indicated at 34^a and 35^a, respectively, and with these graduations datum lines 18^a and 18^b upon the work carrier 18 coact. By this means the adjustment of the two ends of the work carrier 18 with respect to the opposed operative portions of the two wheels may not only be equalized but also exactly predetermined. For example, the pitch of the threaded stops 32 and 33 may be 0.1 inches, and the graduations 34^a and 35^a may represent intervals equal to this pitch. The disc portions 32^a and 33^a of the stops may be divided into one hundred equal parts and these portions, coacting with the vertical members 34 and 35, form convenient verniers by means of which

the elevation of the stops 32 and 33, and hence of the work supported on the work carrier 18, may be directly predetermined to within one-thousandth of an inch.

5 The cylindrical work, generally indicated at 36, is supported upon the upper surface of the work carrier 18 and with the latter in lowermost position and resting upon the stops 32 and 33 it presents the work to the opposed operative portions of the two wheels, which portions may in any suitable manner, as for example by a double-diamond truing device, have been previously brought into exact parallelism. Assuming now, for example, in order to illustrate the use of the vernier adjustment of the two stops, that work of larger diameter is to be operated upon, the wheels 10 and 11 are first adjusted away from one another to the desired extent 10 in order that the opposed operative portions heretofore brought into parallelism may accommodate the enlarged diameter of work to be operated upon. In order, however, that the desired parallel opposed operative 15 portions operate upon the work of larger diameter, the work carrier 18 must be lowered, and hence it will be seen that for each diameter of work operated upon there will be a predeterminedly fixed elevation of the 20 upper surface of the work carrier with respect to the opposed operative portions of the two wheels. By means of the direct-reading indicating adjustments or stops the 25 desired elevation of the work carrier 18 for each diameter of the work operated upon may be exactly predetermined without the necessity of finding this elevation empirically. Thus both time and labor are 30 conserved in making possible the ready and rapid desired adjustment of the work carrier for the varying conditions under which the 35 apparatus must work.

In order to insure the feeding of the cylindrical work along the work carrier 18 in the direction of the axis of the work, the work carrier 18 and the regulating wheel 11 are related to one another so that the path of travel provided for the work by the work carrier and the path of travel of the operative surface of the regulating wheel are inclined with respect to one another so that the regulating wheel 11 may exert a thrust in the desired direction of travel. Preferably I incline the axis of rotation of the regulating wheel 11 with respect to the work carrier 18 and, as viewed in Fig. 1, this relative inclination is clearly shown. It is to be understood, of course, that this relative inclination may be varied to vary the rate of feed, and I may conveniently accomplish this by tilting the work carrier 18 with respect to the supporting lugs 28^a and 29^a of the vertical posts 28 and 29, respectively.

At its left-hand end as viewed in Fig. 1 the work carrier 18 is preferably cut away

as at 37 so that the active work-supporting portion thereof terminates in substantial alignment with the left-hand portions of the operative surfaces of the wheels. The work carrier 18 is thus cut away at its forward end in order to accommodate the enlarged or irregularly shaped portion of the work which, generally indicated at 36, is illustratively shown as taking the form of a bolt having a cylindrical shank 36^a, which it is desired to reduce to cylindrical form, and the enlarged end portion or head 36^b.

The upper face of the work carrier 18 (see Figs. 2 and 3) is inclined toward the operative surface 11^a of the regulating wheel 11 and is, moreover, recessed as at 18^c throughout at least the entire extent of the active supporting portion between the wheels. Within the recess 18^c is inserted a wear strip 38, herein shown illustratively as of square cross section to correspond with the cross section of recess 18^c. The strip 38 is made of a suitably hardened steel and is adapted to be exposed to the cylindrical work operated upon it. The work carrier 18 is provided with a slot 18^d extending inwardly from the recess 18^c so as to permit the screws 39 to clamp the wear strip 38 in position. The wear strip 38, having a plurality of wear surfaces, may be rotated to expose any one of its several wear surfaces to the work and thus provides a convenient and simple means for presenting to the work a new or unworn supporting surface as conditions require. The recess 18^c with the associated clamping screws 39, however, also permits the wear strip 38 to be slidably moved within the recess, and referring now to Fig. 1 it will be seen that I position the wear strip 38 longitudinally of the active supporting portion of the work carrier 18 so that its left-hand end projects beyond the left-hand end portions of the operative surfaces of the two wheels. Thus, in Fig. 1 the projecting end is indicated at 38^a.

Upon the right-hand end portion of the bar forming the carrier 18, and upon the rear side thereof as viewed in Fig. 1, there is detachably secured, as by the cap screws 40 and 41, an auxiliary frame member 42 having two spaced bosses 42^a and 42^b preferably integrally formed therewith and adapted to overlap the upper side of the work carrier 18 so as to be in substantial alignment with the path of travel of the work 36 on the carrier 18. One of the bosses, namely, the forward one, 42^a, is internally threaded to receive an externally threaded sleeve 42^c, and the other boss 42^b is bored out to form with the sleeve 42^c aligned bearings or journals for a plunger rod 43 slidably mounted therein, the sleeve 42^c and boss 42^b slidably supporting the plunger rod 43 in substantial alignment with the path of travel of the work 36 on the carrier 18. It

will be noted that the sleeve is elongated and, by means of its threaded engagement with the boss 42^a may be moved longitudinally of itself toward or away from the wheels and substantially in the direction of the path of travel of the work. The forward end of the sleeve 42^c may thus act as a stop to engage the end of the work, and may be used in conjunction with the stop 38^a or 10 independently thereof. A head 42^e on the sleeve serves for convenient manual adjustment thereof, and a lock-nut 42^d may be employed to lock the sleeve in adjusted position. It should be noted that I prefer to 15 employ both the sleeve 42^c and the stop 38^a to limit the inward movement of the work, as hereinafter explained, and that the stop 38^a acts positively to prevent engagement of the enlarged portion 36^b of the work with 20 the wheels. Intermediate of the bosses 42^a and 42^b there is secured to the rod 43 a vertically extending arm 44 slit or bifurcated at its upper end, as at 44^a. A set screw 44^b in the lower end of the arm 44 is adapted to 25 lock the rod 43 to the arm 44 and engages the flattened portion 43^a of the rod 44 so that the latter may be adjustably secured to the arm 44 with respect to the work 36.

A lever 45 is pivoted as by the cap screw 30 46 at its lower end to the bar 18 and at its upper end is provided with a pin conveniently taking the form of a bolt 47 for slideable engagement with the slotted portion 44^a at the upper end of the arm 44. The upper 35 end of the lever 45 is connected by an operating rod 48 which extends to the left, as viewed in Fig. 1, to the front part of the machine or apparatus where it is formed into a handle portion 48^a for convenient 40 manual operation. The forward end of the operating rod 48 is conveniently supported as by the plate member 49 preferably detachably secured as by the thumb-screw 50 to the upper portion of the protective housing 12 45 encasing the two wheels and substantially at the portion thereof intermediate of the two wheels.

Turning now to the preferred method of 50 operation of this apparatus, the operating lever 25 is first moved in a clockwise direction to raise the carrier 18, as viewed in Fig. 1, and to position its work-supporting surface between more distant parts of the approaching operative surfaces 10^a and 11^a of the two wheels 10 and 11 (see Fig. 2). The work 36 intended to be operated upon is thereupon placed upon the work carrier 18 with the cylindrical portion 36^a between the operative surfaces and with the enlarged end or headed portion 36^b in engagement with the stop or projecting end 38^a of the wear strip 38 and with its right-hand end (as viewed in Fig. 1) abutting against the sleeve 42^c. This position of the work is indicated 55 in full lines in Fig. 1. The inclined sup-

porting surface of the carrier 18 (see Figs. 2 and 3) causes the work 36 to be urged by the action of gravity toward the upwardly moving operative surface 11^a of the regulating wheel 11. This wheel, and hence its 70 operative surface, moves at a relatively low speed, and while the carrier 18 is in its uppermost position, as well as during the inward and outward movements thereof, the work is thus kept out of contact with the 75 surface 10^a of the grinding wheel 10 moving at a suitable grinding speed. Undesired grinding and a consequent marring of the cylindrical portion 36^a of the work is thus 80 during this short period prevented. 80

The work 36 having been thus positioned on the work carrier 18, the operating lever 25 is moved in counter-clockwise direction with a continuous movement, thus permitting the carrier 18 to move inwardly (as seen 85 in Fig. 2) between the operative surfaces of the two wheels and to present the cylindrical portion 36^a of the work 36 to the desired opposed operative portions of these two surfaces. The stops 32 and 33, which have been 90 previously adjusted for the particular diameter of the work as hereinbefore described, limit this inward movement of the work carrier and hence of the work and insure the presenting of the cylindrical portion of the work to the proper opposed operative portions of the two surfaces. The grinding of the cylindrical portion of the work at once commences and during this 95 grinding by the grinding wheel 10 the regulating wheel 11 controls the rotation of the work upon the carrier and at the same time tends to feed the work along the carrier and in a direction toward the right as seen in 100 Fig. 1. The sleeve 42^c, however, prevents a movement or feeding of the work during the ensuing grinding action on the round portion 36^a and thus acts to prevent the enlarged portion of the work from engaging 105 with the abrasive wheels, the stop 38^a insuring this action to take place. In Fig. 1 is shown in full lines this initial position of the work, and it may be noted that during 110 the rotating of the work by the regulating wheel the cylindrical portion 36^a of the work 36 is presented to the grinding wheel for a major grinding action thereon, while the enlarged end portion 36^b is effectively held out of engagement with the two wheels. 115

Thus, after the major grinding operation as above described has taken place, the operator moves the operating bar 48 to the left as viewed in Fig. 1, and thus acting through the pivoted lever 45 and arm 44 moves the plunger 43 (through the sleeve 42^c) also to the left and into engagement with the right-hand end of the work 36 which, as above described, is held against the stop sleeve 42^c during the above grinding operation. The 120 movement of the plunger rod 43 to the left 125

is continued to move the work 36 likewise to the left against the feeding action of the regulating wheel and into substantially the dotted line position indicated in Fig. 1, thus passing that part of the cylindrical portion 36^a of the work 36, heretofore exterior and out of range of the operative portions of the two wheels, into active operative relation to the wheels for grinding action thereon. The operator thereupon releases the operating rod 48 which, with its plunger 43, is returned by the spring 51 to normal. The grinding action continues, this time, however, accompanied by a movement of the work 36 to the right in response to the feeding action of the regulating wheel 11, until the sleeve 42^a halts the movement of the work. This halting, as above described, may, if desired, be supplemented by the stop 38^a, which effectively safeguards the enlarged portion 36^b of the work. The foregoing successive manual (to the left) and automatic (to the right) movements of the work 36 may be repeated as often as desired until the required amount of "finished" grinding action is attained. The operating handle 25 is thereupon moved in clockwise relation to move the carrier upwardly as viewed in Fig. 1, or outwardly between more distant portions of the approaching operative surfaces of the two wheels as viewed in Fig. 2, and the work 36 is ready to be discharged from the carrier. The work 36 may thereupon be ejected from the apparatus by a continued movement to the left of the plunger 43 after the ejection in any suitable manner. When the operator releases the operating rod 48, a tension spring 51 held at one end by a pin 51^a in the bar 18 and connected at the other end to the lever 45 acts to move the ejector rod 43 with its associated operating mechanisms to the right and substantially into the position shown in Fig. 1, whence the apparatus is in readiness to receive upon the work carrier 18 another article to be operated upon, whence the procedure and operation hereinbefore described are repeated.

It will thus be seen that there has been provided in this invention a practical apparatus in which the several objects hereinbefore set forth, as well as many advantages, are achieved. It will be seen that the apparatus is of rugged and durable construction throughout, thus insuring dependable and reliable action and operation thereof and, moreover, that the apparatus is of simple and convenient adjustment throughout. Moreover, certain of the mechanisms above described are readily detachable and thus make possible a wide range of application of the apparatus.

As many possible embodiments might be made of this invention and as many changes might be made in the embodiment above set

I claim as my invention:

1. In apparatus of the general nature of that herein described, in combination, a grinding wheel rotatable at relatively high speed, a regulating wheel rotatable at relatively low speed, a carrier extending between said wheels and adapted to support the cylindrical portion of a body having an enlarged end portion, said wheels presenting operative surfaces traveling in opposite directions whereby said regulating wheel acts to rotate said body on said carrier during operation thereon by said grinding wheel, and means adapted to engage the enlarged end portion of said body to prevent said end portion of said body from entering between the operative surfaces of said wheels, and positioned to permit substantially complete entry of said cylindrical portion of the body between the operative surfaces of said two wheels.

2. In apparatus of the general nature of that herein described, in combination, a grinding wheel rotatable at relatively high speed, a regulating wheel rotatable at relatively low speed, said wheels being adapted to present operative surfaces traveling in opposite directions, means for holding work of round section between the operative surfaces of said two wheels and providing a path of travel for the work with respect to said two wheels, the path of travel of the operative surface of said regulating wheel being inclined with respect to the path of travel of the work provided by said work-holding means, whereby said regulating wheel may act to feed said body along said holding means, a member having an aperture therein and positioned in the path of travel of the work along said work-holding means, and a movable plunger extending through the aperture in said member and adapted upon movement to give said work a retrograde movement.

3. In apparatus of the general nature of that herein described, in combination, a grinding wheel rotatable at relatively high speed, a carrier positioned adjacent the operative surface of said wheel and adapted to support the cylindrical portion of a body having an enlarged end portion, means for simultaneously rotating said body upon said carrier and for feeding said body along said carrier to present the cylindrical portion thereof to said grinding wheel, said carrier being provided with a recess, and means mounted in said recess and extending therefrom in substantial alignment with one end of the face of said grinding wheel and forming a stop with which the enlarged end portion of said body may engage as the body is

fed along said carrier, thereby to prevent entry of said enlarged end portion into operative relation with said grinding wheel while permitting substantially complete entry of the cylindrical portion of said body into operative relation with said grinding wheel.

4. In apparatus of the general nature of that herein described, in combination, a 10 grinding wheel rotatable at relatively high speed, a regulating wheel rotatable at relatively low speed, said wheels being adapted to present operative surfaces traveling in opposite directions, means for holding work 15 of round section between the operative surfaces of said two wheels and providing a path of travel for the work with respect to said two wheels, the path of travel of the operative surface of said regulating wheel 20 being inclined with respect to the path of travel of the work provided by said work-holding means, whereby said regulating wheel may act to feed said body along said holding means, a longitudinally adjustable 25 sleeve positioned in substantial alignment with the work advanced by said regulating wheel along said work-holding means and positioned in the path of travel thereof, and means adapted to pass through said sleeve 30 and movably mounted with respect thereto, said means being adapted upon movement through said sleeve to give the work a retro-grade movement.

5. In apparatus of the general nature of that herein described, in combination, a 35 grinding wheel rotatable at relatively high speed, a carrier mounted adjacent said wheel and adapted to support the cylindrical portion of a body having an enlarged end 40 portion, said carrier being provided with a wear strip exposed for contact by the cylindrical portion of said body, and means for simultaneously rotating said body on said carrier and feeding said body along said carrier for action thereon by said grinding wheel, said carrier terminating adjacent the 45 end of the face of said grinding wheel and said wear strip projecting beyond the end of said carrier to form a stop for engagement by said enlarged portion of said body as the latter is fed along said carrier.

6. In apparatus of the general nature of that herein described, in combination, a 55 grinding wheel rotatable at relatively high speed, a regulating wheel rotatable at relatively low speed, said wheels being adapted to present approaching operative surfaces and opposed operative portions of said surfaces to work presented thereto, a work-carrier 60 extending between said wheels and adapted to support work of round section for action thereon by said wheels, means for moving said work-carrier between said approaching operative surfaces of the two 65 wheels and in a direction to carry the work

into or out of operative relation to the opposed operative portions of the said wheels, and means for maintaining the work out of contact with said grinding wheel during movement of said carrier to carry the work 70 into or out of operative relation with the operative portions of said two wheels.

7. In apparatus of the general nature of that herein described, in combination, a 75 grinding wheel rotatable at relatively high speed, a regulating wheel rotatable at relatively low speed, a carrier extending between said wheels for supporting a cylindrical body thereon, the path of travel provided by said carrier making an angle with 80 the path of travel of the operative surface of said regulating wheel whereby said body is rotated and fed along said carrier, means for limiting the movement of said body along said carrier, and independently acting 85 means for moving said body in reverse direction and out of operative relation to said two wheels.

8. In apparatus of the general nature of that herein described, in combination, a 90 grinding wheel rotatable at relatively high speed, a regulating wheel rotatable at relatively low speed, a carrier extending between said wheels for supporting a cylindrical body thereon, the path of travel provided by said carrier making an angle with 95 the path of travel of the operative surface of said regulating wheel whereby said body is rotated and fed along said carrier, adjustably means adapted to halt the movement of 100 said body along said carrier, and independently acting means for giving said body a reverse movement thereby to discharge said body from said carrier.

9. In apparatus of the general nature of that herein described, in combination, a 105 grinding wheel rotatable at relatively high speed, a regulating wheel rotatable at relatively low speed, a carrier extending between said wheels for supporting a cylindrical body thereon, the path of travel provided by said carrier making an angle with 110 the path of travel of the operative surface of said regulating wheel whereby said body is rotated and fed along said carrier, manually operative means adapted to engage said body and upon operation to discharge said body from said carrier and out of operative relation with respect to said two wheels, a stop member positioned so as to halt the 115 movement of said body along said carrier and acting independently of said last-mentioned means, and spring means for returning said manually operative means to normal position.

10. In apparatus of the general nature of that herein described, in combination, a 120 grinding wheel rotatable at relatively high speed, a carrier mounted adjacent said grinding wheel and adapted to support the cylind- 125

- drical portion of a body having an enlarged end portion, means for simultaneously rotating and feeding said body along said carrier thereby to present the cylindrical portion thereof to said grinding wheel for grinding action thereon, means adapted to be engaged by said enlarged end portion of said body as the latter is moved along said carrier, and positioned to halt the body at such a point that the enlarged portion thereof is prevented from entering into engagement with said grinding wheel, and means for giving said body a reverse movement to discharge said body from said carrier. 11. In apparatus of the general nature of that herein described, in combination, a grinding wheel rotatable at relatively high speed, a carrier mounted adjacent said grinding wheel and adapted to support the cylindrical portion of a body having an enlarged end portion, means for simultaneously rotating and feeding said body along said carrier thereby to present the cylindrical portion thereof to said grinding wheel for grinding action thereon, means adapted to be engaged by said enlarged end portion of said body as the latter is moved along said carrier, thereby to limit the extent of movement of said body on said carrier, and manually operative means adapted to be placed in engagement with the other end of said body and to move said body in reverse direction and out of operative relation with respect to said wheel. 12. In apparatus of the general nature of that herein described, in combination, a grinding wheel rotatable at relatively high speed, a carrier mounted adjacent said grinding wheel and adapted to support the cylindrical portion of a body having an enlarged end portion, means for simultaneously rotating and feeding said body along said carrier thereby to present the cylindrical portion thereof to said grinding wheel for grinding action thereon, means adapted to be engaged by said enlarged end portion of said body as the latter is moved along said carrier, thereby to limit the extent of movement of said body on said carrier, manually operative means adapted upon operation to engage the other end of said body and move said body in reverse direction and out of operative relation to said grinding wheel, and spring means for returning said manually operative means to normal. 13. In apparatus of the general nature of that herein described, in combination, a grinding wheel rotatable at relatively high speed, a regulating wheel rotatable at relatively low speed, a carrier mounted between said wheels and adapted to support the cylindrical portion of a body having an enlarged end portion, the path of travel provided by said carrier making an angle with the path of travel of the operative surface of said regulating wheel thereby to feed said body along said carrier for operation thereon by said grinding wheel, said carrier terminating adjacent one end of the operative surfaces of said wheels whereby said enlarged portion of said body may engage said carrier thereby to halt the movement of said body along said carrier, and manually operative means for moving said body in reverse direction to discharge said body from said carrier and out of operative relation with respect to said wheels. 14. In apparatus of the general nature of that herein described, in combination, a grinding wheel rotatable at relatively high speed, a carrier mounted adjacent said grinding wheel and adapted to support the cylindrical portion of a body having an enlarged end portion, a regulating wheel adapted to rotate and feed said body along said carrier for grinding action thereon by said grinding wheel, an adjustable stop positioned in the path of travel of said enlarged end portion and adapted to be engaged thereby to limit the movement of said body along said carrier, and means acting independently of said adjustable stop and manually operative for moving said body in reverse direction to remove said body from operative relation to said two wheels. 15. In apparatus of the general nature of that herein described, in combination, a grinding wheel rotatable at relatively high speed, a regulating wheel rotatable at relatively low speed, said wheels being adapted to present approaching operative surfaces traveling in opposite directions and to present opposed operative portions of said surface to work presented thereto, a movable carrier extending between said wheels for supporting a body having a cylindrical portion and an enlarged end portion, means for moving said carrier between said approaching operative surfaces and in a direction toward said opposed operative portions thereof with said enlarged end portion of said body exterior of said operative surfaces to present said cylindrical portion to said opposed operative portions, said carrier providing a path of travel for said body inclined with respect to the path of travel of the operative surface of said regulating wheel, and a stop member positioned in the path of travel of said enlarged end portion and adapted to be engaged thereby to limit the movement of said body along said carrier. 16. In apparatus of the general nature of that herein described, in combination, a grinding wheel rotatable at relatively high speed, a regulating wheel rotatable at relatively low speed, said wheels being adapted to present approaching operative surfaces

- traveling in opposite directions and to present opposed operative portions of said surfaces to work presented thereto, a movable carrier extending between said wheels for supporting a body having a cylindrical portion and an enlarged end portion, means for moving said carrier between said approaching operative surfaces and in a direction toward said opposed operative portions thereof with said enlarged end portion of said body exterior of said operative surfaces to present said cylindrical portion to said opposed operative portions, said carrier providing a path of travel for said body inclined with respect to the path of travel of the operative surface of said regulating wheel, means for moving said carrier between said approaching operative surfaces and in a direction toward said opposed operative portions thereof with said enlarged end portion of said body exterior of said operative surfaces to present said cylindrical portion to said opposed operative portions, means associated with said carrier for aligning the cylindrical portion of said body with the operative surface of said grinding wheel, and a stop positioned in the path of travel of said body on said carrier for limiting the movement thereof to prevent said enlarged end portion from being moved into operative relation to said opposed operative portions.
19. In apparatus of the general nature of that herein described, in combination, a grinding wheel rotatable at relatively high speed, a regulating wheel rotatable at relatively low speed, said wheels being adapted to present approaching operative surfaces traveling in opposite directions and to present opposed operative portions of said surface to work presented thereto, a movable carrier extending between said wheels for supporting a body having a cylindrical portion and an enlarged end portion, means for moving said carrier between said approaching operative surfaces and in a direction toward said opposed operative portions thereof with said enlarged end portion of said body exterior of said operative surfaces to present said cylindrical portion to said opposed operative portions, said carrier providing a path of travel inclined with respect to the path of travel of the operative surface of said regulating wheel, means for moving said carrier between said approaching operative surfaces and in a direction toward said opposed operative portions thereof with said enlarged end portion of said body exterior of said operative surfaces to present said cylindrical portion to said opposed operative portions, said carrier being provided with an exposed supporting surface inclined toward the operative surface of said regulating wheel thereby to support the cylindrical portion of said body in alignment with the operative surface of said grinding wheel as said carrier is moved to carry said body toward said opposed operative portions of said two wheels, and means for limiting the movement of said body along said carrier to prevent said enlarged end portion from entering into operative relation to said two wheels.
20. In apparatus of the general nature of that herein described, in combination, a grinding wheel rotatable at relatively high speed, a regulating wheel rotatable at relatively low speed, said wheels being adapted to present approaching operative surfaces traveling in opposite directions and to present opposed operative portions of said surfaces to work presented thereto, a carrier

support a body having a cylindrical portion and an enlarged end portion, said carrier providing a path of travel inclined with respect to the path of travel of the operative 5 surface of said regulating wheel, means for moving said carrier between said approaching operative surfaces and in a direction toward said opposed operative portions thereof with said enlarged end portion of said body 10 exterior of said operative surfaces to present said cylindrical portion to said opposed operative portions, means associated with said carrier for maintaining the cylindrical portion of said body out of contact with the 15 operative surface of said grinding wheel when said carrier is positioned between more distant portions of said approaching operative surfaces, means for moving said carrier in reverse direction to remove said body 20 from said opposed operative portions, and means for giving said body a reverse movement along said carrier to discharge said body therefrom.

21. In apparatus of the general nature of 25 that herein described, in combination, a grinding wheel rotatable at relatively high speed, a regulating wheel rotatable at relatively low speed, said wheels being adapted to present approaching operative surfaces 30 traveling in opposite directions and to present opposed operative portions of said surfaces to work presented thereto, a carrier extending between said wheels adapted to support a body having a cylindrical portion 35 and an enlarged end portion, said carrier providing a path of travel inclined with respect to the path of travel of the operative surface of said regulating wheel, means for moving said carrier between said 40 approaching operative surfaces and in a direction toward said opposed operative portions thereof with said enlarged end portion of said body exterior of said operative surfaces to present said cylindrical portion to said opposed operative portions, said carrier having a supporting surface inclined with respect to the surface of said regulating wheel thereby to urge said body toward said regulating wheel, means for moving said carrier between said approaching operative surfaces and in a direction toward said opposed operative portions thereof with said enlarged end portion of said body exterior of said operative 45 surfaces to present said cylindrical portion to said opposed operative portions and in a reverse direction to remove said body after grinding action thereon from said opposed operative portions, means for limiting the movement of said body along said carrier when said body is presented to said opposed operative portions to prevent the entry therebetween of said enlarged end portion, and means adapted to be operated after said

carrier is moved in reverse direction to give 55 said body a reverse movement along said carrier to take said body out of operative relation from said wheels.

22. In apparatus of the general nature of that herein described, in combination, a 70 grinding wheel rotatable at relatively high speed, a regulating wheel rotatable at relatively low speed, said wheels being adapted to present approaching operative surfaces and opposed operative portions of said surfaces to work presented thereto, a work-carrier extending between said wheels and adapted to support work of round section for action thereon by said wheels, and means for moving said work-carrier between said approaching operative surfaces of the two wheels and in a direction to carry the work into or out of operative relation to the opposed operative portions of the said wheels, said carrier having a supporting surface inclined with respect to the surface of said regulating wheel, thereby to urge the work toward said regulating wheel and to hold the work out of contact with the grinding wheel during movement of said 90 carrier to carry the work into or out of operative relation with the operative portions of said two wheels.

23. In apparatus of the general nature of that herein described, in combination, a 95 grinding wheel rotatable at relatively high speed, a regulating wheel rotatable at relatively low speed, means extending between said wheels and adapted to hold a cylindrical body in operative relation to said two wheels, the path of travel provided by said holding means making an angle with the path of travel of the operative surface of said regulating wheel thereby to feed said body along said holding means, means positioned in the path of travel of said body for limiting the movement of said body along said holding means, said limiting means being provided with a substantially 100 centrally positioned opening, a movable plunger adapted to be passed through said opening to move said body along said holding means in reverse direction, a pivotally mounted lever, and connections between said lever and said plunger adapted upon 105 swinging movement of said lever to give said plunger a substantially rectilinear movement.

24. In apparatus of the general nature of that herein described, in combination, a 120 grinding wheel rotatable at relatively high speed, a regulating wheel rotatable at relatively low speed, a carrier extending between said wheels and adapted to support a cylindrical body in operative relation to said two wheels, the path of travel provided by said carrier making an angle with the path of travel of the operative surface of

said regulating wheel thereby to feed said body along said carrier, a threaded sleeve member positioned in the path of travel of said body relatively fixed means into which

5 said sleeve member is threaded, thereby to permit adjustment of said sleeve member toward or away from said wheels, and a

plunger adapted to pass through said sleeve to move said body in reverse direction along said carrier.

10 In testimony whereof, I have signed my name to this specification this 28th day of December 1922.

LEWIS R. HEIM.
